UNITED STATES PATENT OFFICE.

CHARLES HARDY, OF NEW YORK, N. Y., ASSIGNOR TO AMSCO PRODUCTS, INC., OF NEW YORK, N. Y., A CORPORATION OF NEW YORK.

BINDING POST.

Application filed June 17, 1925. Serial No. 37,652.

To all whom it may concern:

Be it known that I, CHARLES HARDY, a citizen of the United States, and resident of New York city, in the county of Bronx and State of New York, have invented certain new and useful Improvements in Binding Posts, of which the following is a specification.

This invention relates to binding posts, 10 and more particularly to an improved binding post of the type in which the clamping cap and the stem or post are so coordinated as to prevent the withdrawal or removal of the cap from the stem.

15 The principal objects of my present invention comprehend the provision of a binding post having a non-removable clamping cap designed and constructed so that the cap is efficiently guided on the stem for secure clamping operation, the parts of the 20 cap and stem being so coordinated as to maintain the coaxial relation between the same during use; and the provision of a binding post of this nature which may be manufactured at low cost and assembled 25 with ease, and which may be made in a variety of forms.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiments 35 of my invention, and in which:

Fig. 1 is an elevational view with parts shown in section of the improved binding post embodying my invention,

40 Fig. 2 is a perspective view of the same showing the parts in relatively detached relation, exemplifying the manner of assembling the same, and

Fig. 3 is a view of a modification with 45 parts broken away to show the construction thereof.

Referring now more in detail to the drawings and having reference first to Fig. 1 thereof, the binding post of my invention 50 comprises a stem or post generally designated as S, and a clamping cap generally designated as C movable on the post in the performance of the clamping operation, the said stem S and cap C being coordinated 55 to prevent removal or withdrawal of the

cap from the stem during unclamping operation.

The stem S in the preferred construction comprises a threaded shank s adapted for threaded attachment to a suitable support 60 and for receiving a nut 10 which forms a clamping member, the said stem further including a head h on which the cap C is movable, the said head h having a smooth-faced cylindrical body portion 11 and a cylindrical 65 flanged top portion 12, both free from threads so as to provide smooth exterior walls adapted for close slidable mating with co-operating walls of the cap C, all as will be described more in detail hereinafter. 70 The cylindrical body portion 11 of the head h has a diameter preferably larger than that of the shank s, thereby providing a shoulder 13 forming an abutment or stop for the clamping member 10. 75

The clamping cap C comprises a body member 14 having an enlarged cavity 15 open at the top and a reduced portion 16 having a smooth cylindrical interior wall which slidably mates with the cylindrical 80 body portion 11 of the stem, the interior wall of the enlarged cavity 15 being preferably dimensioned to similarly mate with the outer wall of the flanged top portion 12 of the stem head. 85

By providing a close or fitting engagement between the body and flange portions of the stem head h and the interior walls of the cap C, it will be apparent that the clamping cap may be axially moved on the stem head to 90 and from the clamping member 10 without binding and with a close fit to secure an effective clamping operation. Moreover, by the provision of a head having a smooth cylindrical body portion such as 11 and a 95 cap having the interior cylindrical mating wall 16, an elongated bearing for the stem head is provided, which permits the stem to remain always axially disposed relative to the cap, the close fit between these parts, 100 moreover, preventing any entanglement with any conductor clamp between the clamping members. The cylindrical body portion 11 is preferably provided with a conductor receiving transverse orifice 17 located adjacent 105 the clamping member 10.

For axially and rotatably moving the cap on the stem, the head h of the stem is provided with an axially tapped bore 18, 110 and the cap C is provided with a headed

2
screw member 19, the head 20 of which is secured to the cap C, as will be described presently, and the screw portion 21 of which threadedly mates with the axial tapped bore 18 of the head, as will be clearly apparent from a consideration of Fig. 1 of the drawings. If desired, the bore 18 may extend to the transverse orifice 17, as shown in Fig. 1 of the drawings, and the screw portion 21 may be elongated so as to form a clamping element for conductors inserted through the transverse orifice 17.

The body portion 14 and the headed screw member 19 of the cap C are made as separate elements, and are joined together in the assembling operation of the parts, as will be clearly apparent from a consideration of Fig. 2 of the drawings. Referring to this figure, it will be seen that in the manufacturing of the parts, the body portion 14 is open at the top and provided with a marginal upstanding flange portion 22 through which open top the stem S is inserted when the parts are assembled. After the stem 25 S is inserted in the body portion of the cap, the headed screw 19, which is preferably threaded into the head h of the stem prior to the insertion of the latter in the cap body, is secured in position by inwardly crimping the marginal flange portion 22 onto the head 20 of the screw member 19 from the position shown in Fig. 2 to that shown in Fig. 1 of the drawings, fixedly clamping the headed screw to the cap body.

35 The binding post may be made wholly of metal, or may be provided with a decorative head of insulating material, the former being shown in Fig. 1 and the latter in Fig. 3 of the drawings. The body portion 14 of the cap C is provided with a knurled outer wall section 23 which may form a finger grip for the binding post when made wholly of metal, or which may form a gripping surface for a molded insulation head 24 when a decorative head is desired. Preferably the head 20 of the screw member 19 is notched as at 25, this notch serving to receive part of the molded insulating compound, as clearly shown in Fig. 3 of the drawings, whereby the headed screw member is more positively locked to the insulating head and to the body portion 14 of the cap C.

The manner of making, assembling and using the improved binding post of my invention and the many advantages thereof will in the main be fully apparent from the above detailed description thereof. It will be apparent that the parts may be manufactured inexpensively, and may be readily assembled, producing a binding post in which the cap is non-removable when rotated to unclamping position, the said cap being smoothly rotatable on the head of the stem, the cap being so guided on the head as to always maintain the coaxial relation be-

tween the stem and the cap. It will be further apparent that the construction is moreover such that all-metal binding posts with non-removable heads may be manufactured cheaply, the same being adapted for receiving decorative molded insulation coverings. It will be further seen that the mating threads on the stem head and cap are concealed and housed in a manner to prevent and mutilation of the same during use. It will be apparent that while I have shown my invention in the preferred forms, that changes and modifications may be made in the construction shown without departing from the spirit of the invention as defined in the following claims.

I claim:

1. An electrical binding post comprising a stem having a threaded shank adapted to receive a clamping member and having a flanged head provided with a smooth cylindrical exterior wall of a diameter greater than that of the shank, whereby a stop shoulder for the clamping member is provided, the said stem head being also provided with an axial tapped bore open at the top and with a transverse conductor receiving orifice located adjacent said stop shoulder and communicating with the tapped bore, and a clamping cap movable on the stem head to and from the clamping member, said cap being provided with a smooth cylindrical interior wall slidably mating with the smooth cylindrical exterior wall of the stem head and cooperating with said flanged head to prevent cap withdrawal, the cap being also provided with a centrally arranged separate depending screw member fixed to the cap and threadedly mating with the tapped bore of the stem. 95

2. An electrical binding post comprising a stem including a head having a smooth-faced cylindrical body portion and a flanged top portion, and a clamping cap movable on said stem head, said cap being provided with an enlarged cavity for the flanged top portion of the head and with a reduced portion having a smooth cylindrical interior wall slidably mating with the cylindrical body portion of the stem head, the said reduced portion of the cap cooperating with the flanged top portion of the head to prevent withdrawal of the cap from the stem, the said stem head having an axial tapped bore open at the top and the said cap being provided with a centrally arranged separate depending screw member fixed to the cap and threadedly mating with the tapped bore of the stem head. 105

3. An electrical binding post comprising a stem including a threaded shank adapted to receive a clamping member and a head having a smooth-faced cylindrical body portion and a smooth-faced cylindrical flanged top portion, the cylindrical body portion of

125

the head having a diameter greater than that of the shank whereby a stop shoulder for the clamping member is provided, a clamping cap movable on said stem head to and from said clamping member, said cap being provided with an enlarged cavity the wall of which guidingly fits the flanged top portion of the head and with a reduced portion having a smooth cylindrical interior wall slidably mating with the cylindrical body portion of the stem head, the said reduced portion of the cap cooperating with the flanged top portion of the head to prevent withdrawal of the cap from the stem, the said stem head having an axial tapped bore open at the top, and a separate headed screw member fixed to the cap and forming a top closure therefor, the screw member threadedly mating with the tapped bore of the stem head.

4. An electrical binding post comprising a stem including a head having a smooth-faced cylindrical body portion and a smooth-faced flanged top portion, a clamping cap movable on said stem head, said cap being provided with an enlarged cavity the wall of which guidingly fits the flanged top portion of the head and with a reduced portion having a smooth cylindrical interior wall slidably mating with the cylindrical body portion of the stem head, the said reduced portion of the cap cooperating with the flanged top portion of the head to prevent withdrawal of the cap from the stem, the said stem head having an axial tapped bore open at the top, and a separate headed screw member fixed to the cap and forming a top closure therefor, the screw member threadedly mating with the tapped bore of the stem head.

5. An electrical binding post comprising a stem having a head including a smooth-faced cylindrical body portion and a flanged top portion, a clamping cap movable on said stem head, said clamping cap comprising a body member provided with an enlarged open top cavity for the flanged top portion of the head and with a reduced portion having a smooth cylindrical interior wall slidably mating with the cylindrical body portion of the stem head, the construction being such that the stem is insertable through the open top of the cap body, the reduced portion of the cap cooperating with the flanged top portion of the head to prevent withdrawal of the cap from the stem, the said stem head having an axial tapped bore open at the top, the said cap further including a notched headed screw member separate from but fixed to the cap body after the stem is inserted through the same and forming a top closure for the cap, the screw member threadedly mating with the tapped bore of the stem head, and a molded insulation head for the cap, part of the molded insulation being lodged in the notch of the screw member for positively locking the screw member against rotation on the cap.

member fixed to the cap and forming a top closure therefor, the screw member threadedly mating with the tapped bore of the stem head.

5. An electrical binding post comprising a stem having a head including a smooth-faced cylindrical body portion and a flanged top portion, a clamping cap movable on said stem head, said clamping cap comprising a body member provided with an enlarged open top cavity for the flanged top portion of the head and with a reduced portion having a smooth cylindrical interior wall slidably mating with the cylindrical body portion of the stem head, the construction being such that the stem is insertable through the open top of the cap body, the reduced portion of the cap cooperating with the flanged top portion of the head to prevent withdrawal of the cap from the stem, the said stem head having an axial tapped bore open at the top, the said cap further including a notched headed screw member separate from but fixed to the cap body after the stem is inserted through the same and forming a top closure for the cap, the screw member threadedly mating with the tapped bore of the stem head, and a molded insulation head for the cap, part of the molded insulation being lodged in the notch of the screw member for positively locking the screw member against rotation on the cap.

Signed at New York city, in the county of New York and State of New York, this 10th day of June A. D. 1925.

CHARLES HARDY.
